UNITED STATES PATENT OFFICE.

CHARLES D. WHITE, OF NORWICH, CONNECTICUT.

THREAD CATCHER FOR SPINNING FRAMES.

Application filed July 6, 1922. Serial No. 573,104.

To all whom it may concern:

Be it known that I, CHARLES D. WHITE, citizen of the United States of America, residing at Norwich, in the county of New London and State of Connecticut, have invented a certain new and useful Improvement in Thread Catchers for Spinning Frames, of which the following is a full, clear, and exact description.

10 This invention relates to spinning mechanism, and more particularly to a thread catcher for spinning frames.

An important feature of the invention comprises means, which is located beneath the carrier roll of the spinning frame, and will function to reliably catch any thread passing over said roll to the bobbins, which may break during the spinning operation.

20 With the above and other important objects in view, the invention comprises the particular construction and arrangement of parts which will be hereinafter described, and will be pointed out in the appended claims.

25 Figure 1 shows, in front elevation, portions of the spinning mechanism, including the present invention;

30 Figure 2 is a detail view illustrating the bar with thread catchers thereon;

Figure 3 is an enlarged, detail view, of one of the thread catching elements; and

35 Figure 4 is a view, partly sectional, at right angles to Figure 3.

The spinning frame may be of any desired form, as for example, that shown in United States Letters-Patent No. 1,448,984, granted to me March 20, 1923.

Such parts of the frame as are concerned 40 with the present invention, comprise a bracket 3 having vertical slots 38 and screws or bolts 40 for adjustably clamping the bracket to the spinning frame for supporting a suitable number of bearings 15, for a carrier roll 9, and suitable pairs of draft rolls, one of which, 11, is illustrated in Figure 1.

The carrier roll 9 is provided with a plurality of circumferential grooves 10, which constitute guides for the thread as it passes 45 from the draft rolls to said carrier roll, and thence to the bobbins 6, located below the carrier roll. The grooves 10, I have found, perform very satisfactorily the office of guides for the threads as they pass from 50 the draft rolls, and said grooves require no extraneous devices upon the carrier roll to

guide the thread, passing the periphery of said roll.

The thread as it is being spun and laid upon the bobbins 6 occasionally breaks, and 55 in order to catch the loose ends or broken threads I provide a bar 5, preferably having reduced, polygonal or square, end portions 9, which enter openings of the same shape in the bearings 15, each bar 5 being supported 60 between two of such bearings. The bar 5 is equipped with a plurality of pins 7, best shown in Figs. 3 and 4, which may be passed through openings in the bar, and headed or otherwise enlarged at their upper ends to 65 secure them in said bar. The lower portions of said pins are provided with inclined slots 8, which face to one side of the front of the machine. The bar 5 is located below, and somewhat to the rear of the center 70 of the carrier roll 9, and opposite each groove 10 in the carrier roll is located a pin 7. By this construction and arrangement of parts I have found that when one of the threads which passes around a groove 10 75 breaks, the pin 7 with its slot 8 will catch the broken end of the thread and hold it until the thread can be repaired, in the usual manner by one of the attendants whose duty 80 it is to repair these broken threads.

85 It will be obvious that changes may be made in the details of construction, or in the arrangement of the several parts shown, without departing from the spirit of this invention, provided such changes are within 90 the scope of the following claims.

I claim:

1. A machine of the class described having, in combination, a carrier roll provided with a plurality of spaced grooves, a longitudinal bar located below said roll, and pins provided with downwardly inclined thread catching slots therein and projecting from said bar opposite said grooves.

95 2. A machine of the class described having, in combination, a carrier roll provided with a plurality of circumferential grooves, bearings for said roll, a bar located below and to the rear of the center of said roll and having its ends secured in said bearings, and pins projecting downwardly from said bar in alignment with said grooves, said pins having downwardly inclined thread catching slots therein.

100 105 In testimony whereof I have hereunto set my hand this 28th day of June A. D. 1922.

CHARLES D. WHITE.
